United States Patent Office

Des. 216,263
Patented Dec. 9, 1969

216,263

CABINET FOR AN INPUT-OUTPUT DEVICE

Earl K. Stewart, Scotia, N.Y., assignor to General Electric
Company, a corporation of New York

Filed Nov. 27, 1968, Ser. No. 14,698

Term of patent 14 years

Int. Cl. D14—02; D18—01
U.S. Cl. D26—5

FIG.1

FIG.2

FIG.3

FIG.4

FIG.5

FIG.6

FIGURE 1 is a perspective view of a cabinet for an input-output device, showing my new design;

FIGURE 2 is a top plan view;

FIGURES 3 and 4 are side elevational views;

FIGURE 5 is a front elevation view; and

FIGURE 6 is a rear elevation view.

The broken lines are shown for illustrative purposes only.

I claim:

The ornamental design for a cabinet for an input-output device, substantially as shown and described.
